US00D933286S

(12) **United States Design Patent** (10) Patent No.: **US D933,286 S**
Weiss et al. (45) Date of Patent: **** Oct. 12, 2021**

(54) **VAPORIZER CARTRIDGE**

(71) Applicant: **Pax Labs, Inc.**, San Francisco, CA (US)

(72) Inventors: **Alexander Weiss**, Oakland, CA (US); **David Carlberg**, Portland, OR (US); **Timothy McFarland**, San Francisco, CA (US); **Devin Spratt**, Sunnyvale, CA (US)

(73) Assignee: **PAX Labs, Inc.**, San Francisco, CA (US)

(**) Term: **15 Years**

(21) Appl. No.: **29/702,220**

(22) Filed: **Aug. 16, 2019**

(51) LOC (13) Cl. **27-02**

(52) U.S. Cl.

USPC **D27/162**

(58) **Field of Classification Search**

USPC D27/162, 163–170, 101, 100, 172, D27/174–176, 173, 185–194; D13/103, D13/107; D23/360, 363, 366; D24/110, D24/100.5

CPC A24F 1/30; A24F 1/02; A24F 1/00; A24F 47/008; A24F 47/002

(57) **CLAIM**

The ornamental design for a vaporizer cartridge, as shown and described.

DESCRIPTION

FIG. 1 is a right side, front, and bottom perspective view of a vaporizer cartridge of our design;

FIG. 2 is a left side, front, and top perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dashed broken lines illustrate portions of the vaporizer cartridge that form no part of the claimed design.

1 Claim, 7 Drawing Sheets
